UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

LINE SETTING AND CASTING MACHINE FOR PRODUCING MIXED COPY.

1,070,947.

Specification of Letters Patent. Patented Aug. 19, 1913.

Application filed November 15, 1909. Serial No. 528,096.

To all whom it may concern:

Be it known that I, HEINRICH DEGENER, 26 Hollmannstrasse, Berlin, German Empire, manager, having invented certain new and useful Improvements in or Relating to Line Setting and Casting Machines for Producing Mixed Copy, do hereby declare that the following is an exact specification of the same.

- 10 In line setting and casting machines of the Mergenthaler type in which withdrawable bars are arranged at different levels in the collector for collecting the matrices, there are disadvantages due to the fact that 15 it is very difficult to determine the exact moment at which the bar is to be withdrawn. In setting mixed copy the compositors generally catch the matrices in the top position and then to turn or tip into the lower position those matrices which were to be set in the ordinary type.

It is possible to overcome the difficulties met with in collecting the whole line in the upper position, by dividing the assembling 25 elevator device and lifting the front portion, after collecting, so that the matrices previously collected in the lower position, should be brought into the upper position. This however, led to the further disadvantage that 30 the space wedges were caught only with one eye or lug and consequently assumed an oblique position.

The disadvantage in question is obviated by the present invention.

- 35 A construction according to this invention is illustrated in the accompanying drawings in which—

Figure 1, is a front elevation, partly in section; Fig. 2 a cross-section through the 40 device in the position in which the collection is effected, and Fig. 3 shows the same in the position in which the matrices are tipped or turned.

The assembling elevator device *a* is generally of the known construction. It is provided on the back with a fixed ledge *d* and on the front is arranged in the known manner a bracket or stirrup *f* which is pivoted to the elevator, as shown in the drawing and 45 can be tipped forward. The front ledge *e* for catching the matrices is vertically adjustable. To that end, it is mounted on a slide *g* vertically guided in the assembling elevator. The vertical up and down movement 50 is obtained by means of an eccentric *h* op-

erated by a knob *i* on the front of the assembling elevator. The ledge is arranged so that in the lower position of the slide *g* it is situated in a horizontal plane with the ledge *d*, while in the upper position of the 60 slide *g*, the ledge *e* of the same is higher to the extent of the distance of the characters arranged on the matrices.

The composing is effected in any desired manner whether italics or ordinary type is 65 to be set, always in the lower position of the slide *g*, so that the matrices are collected in their lower position. The spaces *p* are collected as usual and come to rest with both their eyes or lugs on the one hand against the back wall *r* of the assembling elevator, and on the other hand against the upper edge *s* of the bracket *f*.

If the line is to be cast in ordinary type, it is sent to the casting point in the usual manner after the collecting has been effected in the manner described. If, however, it is to contain italics, the whole line is first brought into the upper position by turning the eccentric *h*, after the collecting 75 has been previously effected as described. The matrices are then standing on the ledge *e* only. For the purpose of bringing the matrices, which are to be cast in ordinary type in the lower position, the bracket *f* 80 is then tipped to the position shown in Fig. 3 and those matrices which are to be cast in ordinary type are tipped forward by hand as illustrated in Fig. 3, so that their lugs resting on the ledge *e*, lose their support 85 and the matrices fall downward. If the matrices are then straightened again, either by hand or by turning back the bracket *f* they will come to rest with their back lower lugs on the ledge *d* and will be in the lower 95 position.

If the slide *g* is provided with two ledges *e* and *e'* as shown in Figs. 2 and 3 of the drawing the matrices turned into the lower position rest on the two ledges *d* and *e'*. 100 However the ledges *e'* can be dispensed with.

After the transfer of the line from assembling elevator to an adjacent delivery channel, the slide *g* is always brought back into the lower position by turning the eccentric. If the composed line is to be cast entirely in italics, the slide *g* is brought, after the setting or composing, into the upper position, and the line sent off in that position. 105 110

In order to fix the lower position of the slide *g* there are provided stop pins *k* arranged on the top side of the elevator front part (Fig. 1) which limit the movement 5 downward. The upper position is fixed by the stop *m* arranged at the bottom of the slide *g* (Figs. 2 and 3) which comes to rest against the edge *n* of the assembling elevator.

10 Having now particularly described and ascertained the nature of my invention and in what manner the same is to be performed, I declare that what I claim is:

1. In a linotype machine a device for producing mixed matter containing in combination a ledge on which the matrices are collected, said ledge being vertically movable for the purpose of raising the whole set matrix line and to enable the matrices to be 15 tipped into a lower position and a second immovable ledge for supporting the matrices tipped from the raised movable ledge in their lower position.

2. In a linotype machine a device for producing mixed matter containing in combination a ledge on which the matrices are collected, said ledge being vertically movable for the purpose of raising the whole set matrix line and to enable the matrices 20 to be tipped into a lower position and a second immovable ledge for supporting the matrices tipped from the raised movable ledge in their lower position, said movable ledge, if raised, holding the matrices in the 25 position, in which the lower character is cast, and if lowered being in one plane with the said immovable ledge.

3. In a linotype machine a device for producing mixed matter containing in combination a ledge, on which the matrices are collected, said ledge being vertically movable for the purpose of raising the whole set matrix line and to enable the matrices to be 30 tipped into a lower position, a second immovable ledge for supporting the matrices tipped from the raised movable ledge in their lower position, and parts catching the 35 spacers on both their lugs, whatever the position of the collecting ledge.

4. In a linotype machine a device for producing mixed matter containing in combination a ledge, on which the matrices are collected, said ledge being vertically movable for the purpose of raising the whole set matrix line and to enable the matrices to be 40 tipped into a lower position, a second immovable ledge for supporting the matrices tipped from the raised movable ledge in their lower position, parts catching the 45 spacers on both their lugs, whatever the 50 position of the collecting ledge and means for moving the collecting ledge independently of the spacer-catching parts.

5. In a linotype machine, the assembler 55 wherein the line is composed and provided with a relatively vertically adjustable supporting ledge whereby the line of matrices may be composed at one operative level and thereafter shifted as a whole to a different operative level therein. 70

6. In a linotype machine, the assembler provided with a plurality of means to support the composed line of matrices at different relative operative levels, the said means being relatively adjustable so as to 75 act conjointly also in supporting the composed line at the same level.

7. In a linotype machine, the assembler provided in one of its side walls with a matrix supporting ledge and in its opposite 80 side wall with a second matrix supporting ledge, the said ledges being movable into and out of registry with each other, so as to act conjointly in supporting the matrices at the same level or independently in supporting 85 the matrices at different relative levels.

8. In a linotype machine, the assembler provided in one of its walls with two matrix supporting ledges and in its opposite wall with a single matrix supporting 90 ledge, the parts being relatively movable to bring the single ledge into registry with either one of the other two.

9. In a linotype machine, the assembler wherein the line is composed and provided 95 with a supporting ledge adjustable to different vertical positions within the assembler so as to support the composed line of matrices at different operative levels therein, and provided further with independently mounted spacer supporting means; whereby the matrices may be adjusted relatively to the spacers. 100

10. In a linotype machine, the assembler wherein the line is composed and provided 105 with a supporting ledge adjustable to different vertical positions within the assembler so as to support the composed line of matrices at different operative levels therein, and provided further with an independently mounted swinging bracket to support the spacers; whereby the matrices may be 110 adjusted relatively to the spacers.

11. In a linotype machine, the assembler wherein the line is composed and provided 115 with a device to support the entire line of matrices at a common level, the said supporting device being adjustable vertically in relation to the assembler so as to support the line in different operative positions therein. 120

In witness whereof I have hereunto set my hand in presence of two witnesses.

HEINRICH DEGENER.
